US00D886499S

(12) United States Design Patent (10) Patent No.: US D886,499 S
Davis et al. (45) Date of Patent: * Jun. 9, 2020

(54) TABLE

(71) Applicant: WALKER EDISON FURNITURE COMPANY LLC, Salt Lake City, UT (US)

(72) Inventors: Matthew Davis, Murray, UT (US); Brad Bonham, Draper, UT (US); Richard Packer, Kaysville, UT (US)

(73) Assignee: Walker Edison Furniture Company LLC, Salt Lake City, UT (US)

() Term: 15 Years

(21) Appl. No.: 29/654,952

(22) Filed: Jun. 28, 2018

(51) LOC (12) Cl. 06-03

(52) U.S. Cl.

USPC D6/691.9; D6/655; D6/691.8

(58) Field of Classification Search

USPC D6/641, 642, 655, 685, 686, 691, D6/691.1–691.9

CPC A47B 7/00; A47B 13/00; A47B 13/02; A47B 13/04; A47B 13/06; A47B 13/08; A47B 13/12

(57) CLAIM

The ornamental design for a table, as shown and described.

DESCRIPTION

FIG. 1 is a front perspective view of a table showing the new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right elevation view thereof; and,

FIG. 7 is a left elevation view thereof.

The broken lines in the drawings are for the purpose of illustrating portions of the article that form no part of the claimed design.

1 Claim, 4 Drawing Sheets
